Mark Campbell INVENTOR.

BY
Walter F. Murray ATTORNEY.

UNITED STATES PATENT OFFICE.

MARK CAMPBELL, OF CINCINNATI, OHIO.

TABLE PAD.

Application filed February 2, 1921. Serial No. 441,937.

To all whom it may concern:

Be it known that I, MARK CAMPBELL, a citizen of the United States of America, and resident of Cincinnati, in the county of 5 Hamilton and State of Ohio, have invented a new and useful Improvement in a Table Pad, of which the following is a specification.

An object of my invention is to provide a 10 simple, cheap, efficient and serviceable table pad.

Another object is to provide a firm but comparatively light pad.

These and other objects are attained by 15 the means described herein and disclosed in the accompanying drawing in which:

Fig. 1 is a fragmental perspective view of a table having a pad embodying my invention disposed thereupon.

20 Fig. 2 is an enlarged sectional view on line 2—2 of Fig. 1.

My invention comprises a center sheet A of suitable material, such as cardboard, having mounted upon its opposite sides and secured thereto the backing sheets B upon which are mounted the corrugated sheets C. The backing sheets and the corrugated sheets are preferably made of cardboard or some similar substance. The corrugated 25 sheets C engage the center sheet A and the corrugations thereof extend preferably at substantially right angles to one another. A covering D, of muslin or any other suitable material, extends about and over the 30 backing sheets B and is preferably secured thereupon by means of rows of stitching E passing through the muslin cover, the backing sheets, the corrugated sheets and the center sheet. Edging F is secured along 35 the edge of the pad by one or more rows of stitching E. The edging F may be of any

suitable material such as muslin. Pads constructed in this manner may be made in any size, shape, and form, may be sectional and may have its sections hingedly secured to 45 one another in a manner well known and common to the art.

What I claim is:

1. As a new article of manufacture, a 50 table pad comprising a center sheet, corrugated sheets mounted upon the center sheet and having their corrugations disposed substantially at right angles to one another, backing sheets mounted upon the corrugated sheets, a cover extending over the backing 55 sheets, and a row of stitching passing through the cover, the backing sheets, the corrugated sheets and the center sheet.

2. As a new article of manufacture a 60 table pad comprising a center sheet, corrugated sheets mounted upon the center sheet and having their corrugations disposed substantially at right angles to one another, backing sheets mounted upon the corrugated sheets, a cover extending over the backing 65 sheets, edging extending about the edge of the pad, and rows of stitching securing the edging, the cover, the backing sheets, the corrugated sheets and the center sheet upon one another.

3. As a new article of manufacture, a table 70 pad comprising corrugated sheets having their corrugations disposed at an angle to one another, backing sheets mounted on the corrugated sheets, a cover extending over the 75 backing sheets, and the cover, the backing sheets, and the corrugated sheets being fixedly mounted upon one another.

In testimony whereof, I have hereunto subscribed my name this 29th day of January, 80 1921.

MARK CAMPBELL.
